UNITED STATES PATENT OFFICE.

CHARLES L. LEE, OF DAYTON, OHIO, ASSIGNOR TO GENERAL MOTORS RESEARCH CORPORATION, OF DAYTON, OHIO, A CORPORATION OF DELAWARE.

TRUING TOOL.

Application filed January 17, 1923. Serial No. 613,104.

To all whom it may concern:

Be it known that I, CHARLES L. LEE, a citizen of the United States of America, residing at Dayton, county of Montgomery, 5 and State of Ohio, have invented certain new and useful Improvements in Truing Tools, of which the following is a full, clear, and exact description.

This invention relates to improvements in 10 internal combustion engines, and more particularly to those of the air cooled type wherein the cylinder fins are comprised of a soft metal such as copper.

It can be readily appreciated that an engine cylinder, having its fins constructed of copper or other soft metal, will, in the process of manufacture or while in the hands of the user or of a garage repairman, be subjected to having its fins distorted from their 20 normal shape and thus reduce or restrict the flow of cooling air therethrough.

The present invention, therefore, provides means for truing or ironing the fins back to their normal shape.

25 Further objects and advantages of the present invention will be apparent from the following description, reference being had to the accompanying drawings, wherein:

Fig. 1 is a perspective view of an engine 30 cylinder of the air cooled type, showing the application of the truing tool to the fins.

Fig. 2 is a perspective view of the truing tool.

Fig. 3 is a bottom plan view of the tool 35 shown in Fig. 2.

The present invention contemplates an operating means to which are attached truing members for engaging simultaneously both the inner and outer surfaces of a fin, 40 preferably of the loop type, although the invention may be adapted for use with other types of fins equally well. These truing members are provided with substantially plane surfaces, so that when brought into contact with the surfaces of the fin loop they render those surfaces substantially plane. The truing members are preferably constructed as to be resilient with respect to each other. It can readily be seen that if 45 there were not some resiliency between these members, damage might occur to the loop when the truing device is brought into use, especially if the loop is constructed of soft metal such as copper. It is not necessary 50 that this truing device should render the

loop substantially plane in one operation. The loop may be trued up gradually so as to prevent serious injury to the same.

Referring to the drawings, and more particularly to Fig. 1, the engine cylinder 20 has the fin loops 21 attached thereto in any suitable manner, such as disclosed in the co-pending application of Charles F. Kettering, Serial No. 514,014, filed November 9, 1921.

In Fig. 2 the frame 22 has attached at its lower extremity the ironing fingers 23 in any suitable manner, such as by riveting or welding. The fingers 23 are somewhat resilient with respect to frame 22 and pilot 27 and frame 22 and 27 are somewhat resilient with respect to the operating means so as to yield slightly with respect to the fin. These fingers 23 are slightly curved, as at the point 23^a, to permit the same to gradually come 75 into contact with the outer surface of the fin loop. This construction makes it easier for the operator to start the truing tool on its downward path for the truing operation. At the opposite end of the frame 22 there are 80 attached the straps 24, between which is located the handle 25. The strap members are so formed as to provide a shoulder 26. The pilot 27 is attached to the straps 24 through means of rivets 28, or by welding, 85 and has a cross section adapted to fit on the inside of the fin loops 21.

The operation of the truing tool is as follows:

The operator grasps the device by the handle 25 and inserts the pilot 27 on the inside of the fin loop 21, the ironing fingers travelling on the outside of the fin loop. It will be noted that the pilot travels in advance of the ironing fingers, thus preparing 90 the work to be done by the ironing fingers. The pilot is then forced downward until its movement is stopped by the abutment of the shoulder 26 against the top of the cylinder. The operator then continues to move 100 the truing tool up and down in a vertical direction until the surfaces of fin loop has been completely ironed out by the ironing fingers and rendered substantially plane. The resiliency of the truing elements is sufficient 105 to permit the ironing or truing operation without damage to the fin material especially when thin soft metal is used.

While the method herein described, and the form of apparatus for carrying this 110

method into effect, constitute a preferred embodiment of the invention, it is to be understood that the invention is not limited to this precise method and form of apparatus, and that changes may be made in either 5 without departing from the scope of the invention which is defined in the appended claims.

What I claim is as follows:

- 10 1. In a device for truing fins, the combination with operating means, of members attached to said means, said members providing substantially plane surfaces adapted to engage simultaneously upon opposite 15 sides of a fin in order to render the fin substantially plane.
- 20 2. In a device for truing fin loops, the combination with operating means, of means for engaging the interior surface of the loop, and means for engaging the outer surface of the loop simultaneously with engagement of the inner surface.
- 25 3. In a device for truing fin loops, the combination with operating means, of a pilot member adapted to enter a fin loop and having plane surfaces adapted to engage the interior surface of the loop, and members extending adjacent the pilot member and spaced therefrom for pressing the fin loop 30 against the pilot member.
- 35 4. In a device for truing fins, the combination

with operating means, of members mounted on said operating means and having truing surfaces adapted to be resilient with respect to each other so as to yield 35 with respect to the fin.

5. In a device for truing fin loops, the combination with operating means, of a pilot member attached thereto and adapted to fit within a fin loop and engage the inner 40 surface thereof, and ironing fingers extending adjacent the pilot member but spaced therefrom for pressing the exterior surface of the fin loop against the pilot member in order to render the fin loop substantially 45 plane.

6. In a device for truing fin loops, the combination with operating means, of a pilot member attached thereto and having its operating end positioned in advance of 50 a set of ironing fingers, said ironing fingers extending adjacent the pilot member but spaced therefrom for pressing the exterior surface of the fin loop against the pilot member in order to render the fin loop substantially 55 plane.

In testimony whereof I hereto affix my signature.

CHARLES L. LEE.
